UNITED STATES PATENT OFFICE.

GUSTAV A. HASSEL, OF MCKEESPORT, PENNSYLVANIA, ASSIGNOR TO PITTSBURGH STEEL FOUNDRY CORPORATION, OF GLASSPORT, PENNSYLVANIA, A CORPORATION OF PENNSYLVANIA.

ANNEALING BOX.

Application filed June 17, 1926. Serial No. 116,580.

The invention relates to boxes for sealing sheet or other metal against the ingress of oxygen while being heated, and has particularly to do with annealing boxes of the type which consists of a base having an upturned peripheral flange, and a hood having its lower edge resting upon the base and forming with the flange of the base a groove for the reception of luting or sealing material. In the use of these annealing boxes, considerable difficulty has been encountered by reason of the warpage of the sides of the hoods, particularly at their lower edges. When this warpage takes place during an annealing operation, as it frequently does, the edges of the hood either move outwardly or inwardly of their normal positions. This breaks the seal and permits the flow of an oxidizing atmosphere into the hood. The object of this invention is to provide an annealing box of the type explained with simple and effective means for preventing lateral movements of the lower edge of the hood, the means being such as will not become impaired by high heat to which such boxes are normally subjected in service.

In accordance with the present invention means are provided for securely locking the hood to the base of an annealing box in the region where the warping or distortion is most pronounced, that is, between the corner or end portions of the box, or at such intermediate portions as may be desired. To firmly secure the hood and base a block of suitable shape to engage complementary shaped portions of the base and hood is secured as by a wedge to clamp the hood to the base member. By means of the clamping blocks the hood becomes firmly seated on the base, and the sides of the hood, which are ordinarily free to become distorted, are restrained against movement.

The invention is illustrated in the accompanying drawings of which Fig. 1 is a view partially in side elevation and partially in section of an annealing box; Fig. 2 a cross sectional view thereof taken along the line II-II, Fig. 1; and Fig. 3 a top plan view of the portion of the annealing box in which the wedge-block is secured.

Referring to the several figures of the drawing, the structure therein illustrated comprises a base 1 provided with grooved

runways 2 for the reception of balls, bottom reinforcing ribs 3, a vertically extending peripheral flange or rim 4, and lugs 5, the latter being arranged in pairs in spaced-apart relation either centrally of the longitudinal dimension of the base, or at such intermediate portions thereof as may be desired. A hood 6 of the usual or any desired reinforced rib construction is adapted to rest upon the upper face of base 1 within the rim or flange portion 4 and within the vertically extending lugs 5. The hood is provided with arms or lugs 7 for receiving hooks for hoisting by means of which it is lifted and lowered from and onto base 1.

As shown in Fig. 2, base 1 and hood 6 are provided with mortised grooves 8 for receiving a dove-tailed block 9 having a central opening 10 for receiving a wedge 11. The dimensions of block 9 are such as to fit between the projecting lugs 5, the latter being provided with openings for receiving the wedge member 11 in alignment with the central opening 10 of the block. The wedge 11 is driven through the openings of the lugs 5 and the central opening of the clamping block 9, as shown in Fig. 1, to drive the block against the mortised seating grooves 8 of the base and hood to firmly clamp the latter to the former for the purpose hereinbefore stated.

Although but a single pair of blocks are shown in the drawing disposed midway between the ends of the annealing box, it is evident that two or more such clamps may be provided on each side of the annealing box, and also at the respective ends thereof in accordance with the clamping action it is desired to obtain for a given sized annealing box. It is also evident that various forms of clamping blocks may be used in place of those illustrated, it being characteristic of the blocks and their cooperating elements that they are so formed that their usefulness does not become impaired by being periodically subjected to high temperatures.

By using the clamping means herein provided, the sides of an annealing box hood are so held against distortion that the seal at their edges does not become broken during an annealing operation.

Although this invention is herein illustrated in its preferred embodiment it will

be obvious to those skilled in the art that various modifications may be made in the details of construction and in the arrangement of the several cooperating parts without departing from the principles herein set forth.

I claim:

1. In an annealing box the combination of a base, a hood, and means for securely locking said base and hood, said means comprising a plurality of blocks adapted for locking engagement with said base and hood, and wedges extended through said blocks and through openings provided in said base.
2. In an annealing box the combination of a base having a plurality of mortised offset portions, a hood adapted to seat thereon, said hood having mortised portions corresponding to and registering with the mortised portions of said base, blocks shaped complementary to the mortised portions of said base and hood, and means for interlocking said blocks, base and hood.

3. In an annealing box the combination of a base having a plurality of mortised offset portions, a hood adapted to seat thereon, said hood having mortised portions corresponding to and registering with the mortised portions of said base, blocks shaped complementary to the mortised portions of said base and hood, and wedges extending through said blocks into openings provided in said base for interlocking said blocks, base and hood.

4. In an annealing box the combination of a base having spaced-apart vertically extending lugs, a hood adapted to seat on said base intermediate said lugs, clamping blocks disposed between said lugs and adapted to cooperatively engage said base and hood, and wedges extending through openings in said blocks and the lugs of said base to interlock the said base and hood.

In testimony whereof, I sign my name.

GUSTAV A. HASSEL.
